Francis H. Richards.

UNITED STATES PATENT OFFICE.

FRANCIS H. RICHARDS, OF SPRINGFIELD, MASSACHUSETTS, ASSIGNOR, BY DIRECT AND MESNE ASSIGNMENTS, TO THE RICHARDS FASTENER COMPANY, OF NEW BRITAIN, CONNECTICUT.

METHOD OF MAKING PAPER-FASTENERS.

SPECIFICATION forming part of Letters Patent No. 341,432, dated May 4, 1886.

Application filed November 4, 1885. Serial No. 181,835. (No model.)

To all whom it may concern:

Be it known that I, FRANCIS H. RICHARDS, a citizen of the United States, residing at Springfield, in the county of Hampden, State 5 of Massachusetts, have invented certain new and useful Improvements in Methods of Making Paper-Fasteners, of which the following is a specification.

This invention relates to methods for making of fabric that class of paper-fasteners described and claimed in my application Serial No. 178,073, filed September 24, 1885, which fasteners consist of two thicknesses united at about the middle, and have four free ends.

15 The invention has for its object the making of such fasteners of a single piece of textile fabric, as hereinafter set forth.

In the drawings accompanying and forming a part of this specification, Figure 1 is a side 20 view of a piece of woven or knitted fabric. Fig. 2 is an edge view of the same. Fig. 3 is an enlarged end view of a strip cut from said fabric. Fig. 4 is a similar side view of the same. Figs. 5 and 6 are respectively a great- 25 ly-exaggerated side and an end view of the strip of woven fabric, showing how the threads are arranged.

Similar characters designate the same parts in all the figures.

30 In carrying my improved method into effect I first prepare a woven or knitted fabric, A, which consists of two thicknesses, C D, formed into one at regular intervals, as at E, during the process of manufacture. This fabric is 35 then cut on lines *a a b b*, Figs. 1 and 2, thus producing the strip shown in Figs. 3 and 4, having the four free edges 2, 4, 6, and 8, all united at E. From this strip the fasteners are cut, as indicated by dotted lines at *d*, *e*, and *f*.

40 Fig. 3 is substantially an edge view of the completed fastener, which has the four similar free ends, 2, 4, 6, and 8. The outer (or inner) surfaces of all the ends are now coated with an

adhesive substance—as glue, gum-arabic, or the like—when the fastener is ready for use. 45

Of the two kinds of textile fabric above mentioned I prefer to use that produced by the method of weaving. Such a fabric I have shown on a very large scale in Figs. 5 and 6. Each of the two parts C and D is composed of 50 the usual warp and filling threads, of which those of the warp are in some way interlocked at E with the filling or woof of the opposite part. This is readily accomplished by means of ordinary Jacquard looms by methods that 55 are well known to those familiar with that class of weaving machinery. The method I prefer is shown in Fig. 6, wherein the warp-threads cross over each other at E, those from end 2 running into end 8, and from end 60 4 into end 6. Two of these threads are des- 65 signated, respectively, by 3 and 5, the woof being designated by 9. In practice I consider that it will be sufficient if about one-half of the warp-threads are crossed, as de- 70 scribed, the remainder continuing each in the same part C or D.

In this application I make no claim to the improved fabric herein described, having de- 75 scribed and claimed the same in another ap- 70 plication of even date herewith.

Having thus described my invention, I claim—

The improved method herein described of 75 making flexible paper-fasteners of the class specified, it consisting in first preparing the material into a double-thickness woven or knitted fabric united substantially as de- 80 scribed, and then cutting the fastener from the fabric, the united part thereof being at about the middle of the fastener, substantially as set forth.

FRANCIS H. RICHARDS.
